UNITED STATES PATENT OFFICE.

JOHN J. HARPAIN, OF THE UNITED STATES NAVY.

SUBMARINE TORPEDO-BOAT.

No. 800,101.

Specification of Letters Patent.

Patented Sept. 19, 1905.

Application filed February 21, 1905. Serial No. 246,736.

To all whom it may concern:

Be it known that I, JOHN J. HARPAIN, a citizen of the United States, serving on board the United States ship *Marblehead*, at present 5 stationed at San Francisco, California, have invented certain new and useful Improvements in Submarine Torpedo-Boats; and I do hereby declare the following to be a full, clear, and exact description of the invention, 10 such as will enable others skilled in the art to which it appertains to make and use the same.

My invention relates to improvements in submarine torpedo-boats of that class in which the torpedoes are carried outside of the boat 15 and may be launched when desired by a member of the crew of the boat.

My invention relates more especially to tor- 20 pedo-boats of small type, which may be normally carried aboard ship and which may be hoisted in or out when desired. The boat carries a small crew and is driven by any suitable source of power, which application of power not being a part of my present invention will not be described herein.

25 My invention will be understood by reference to the accompanying drawings, in which the same parts are indicated by the same letters and numerals throughout the several views.

30 Figure 1 is a side elevation of the boat, parts of the interior being shown in dotted lines. Fig. 2 is a front view of the boat and the torpedoes carried thereby. Fig. 3 is a detail showing the means for securing a tor- 35 pedo to the side of the boat. Figs. 4 and 5 are details showing in side elevation and in rear elevation the hatch-cover in the raised position, it being shown in the closed position in Figs. 1 and 2. Fig. 6 is a plan view show-

40 ing one of the torpedoes as attached to the boat, parts being broken away. Fig. 7 is a front view, on an enlarged scale, of a part of the torpedo-detaching apparatus shown in Fig. 6. Fig. 8 shows the inboard levers and 45 ratchet-and-pawl arrangements for detaching two of the torpedoes. Fig. 9 is a side elevation, on an enlarged scale, showing details of the means for detaining the torpedo and for releasing the same when desired. Fig. 10

50 shows one of the detachable weights attached to the bottom of the boat. Fig. 11 is a dia- 55 gram showing the operation of the immersion-rudders. Fig. 12 is a plan view of the device shown in Fig. 11, also shown diagrammatically; and Fig. 13 is a diagram showing means for filling and emptying the ballast-tanks.

A represents the hull of the boat.

B represents a guard-rail which projects from the bow of the boat nearly to the stern and is spaced therefrom by suitable tie-rods 60 B', on which tie-rods the immersion-rudders are pivoted, as will be hereinafter described.

The torpedoes D are held in rings C', which rings are carried by braces C, secured to the guard-rails B, and the braces C, secured to 65 the hull of the boat. The two rings C' are connected by channel-bars C², which are made in two parts, hinged together, as at c⁰, so that the outer portions of the ring may swing down, as shown in dotted lines at C⁰ in Fig. 3. 70 Projecting into the longitudinal groove c between these channel-bars are lugs d on the top and bottom of the torpedo, and thus these channel-bars and lugs serve to hold the tor- 75 pedoes and to guide them in launching with their axes parallel to or, if desired, at a pre- determined angle relative to the longitudinal axis of the boat. These torpedoes are preferably of the ordinary type, such as the White- 80 head, and are provided with suitable propel- 85 ling power and mechanism and also with the well-known Obry gear, (not shown,) which is set in operation by means of a suitable latch d' (see Fig. 1) as the torpedo is launched. This latch also sets the motive power in op- 90 eration as the torpedo is launched; but the internal mechanisms of the torpedo are in no sense a part of my invention and will not be further described, this starting of the Obry gear and of the propelling mechanism of the 95 torpedo being well known in the art.

E represents a drum mounted on the shaft E', which shaft is connected to the spiral spring E² and carries a ratchet-wheel E³, nor- 95 mally controlled by a ratchet-and-pawl ar- range- 100 ment, such as that shown in Fig. 8, in which the upper ratchet-wheel is controlled by the pawl k, the rod k', and the arm k², which is operated by the hand-lever K. The lower ratchet-wheel is controlled by the pawl k³, the rod k⁴, and the hand-lever K'. Thus the ratchet-wheel may be released, and the shaft E' may be caused to revolve under the action of the spring E² by the motion of a hand- 105 lever contained within the boat. The spring E² is wound up from the outside of the boat by means of a crank E⁰, (shown in dotted lines in Fig. 9,) which is attached to the squared end e' of the shaft E'. Wound on the drum E is a wire rope or chain F, which passes over a pulley c⁰, which is mounted in the guide- 110 way c high enough up to clear the lug d when

the torpedo is launched. This rope F is connected to a hook F', which has an arm f, which engages part of the tail-frame d' of the torpedo. The drum E has its flanges notched, as 5 at e, to engage the arm h' of the bell-crank lever H, which is pivoted at h^o to one of the channel-bars, and its opposite arm carries the latch h, which projects in front of one of the guide-lugs d of the torpedo, and thus this 10 latch holds the torpedo against release in the initial position. The arms h of the bell-crank lever are held in such a position as to keep the latch h in engagement by means of the notches e and against the action of the springs 15 h². These springs are normally under tension and hold the latch h clear of engagement with the lug d when the drum E is rotated to release the torpedo in the direction indicated by the arrow in Fig. 9. The latch h is bifurcated, as shown in Fig. 7, to permit the passage 20 through the fork thereof of the wire rope or chain F.

The boat is preferably raised or lowered relative to the surface of the water "on an even keel" or at any fixed angle relative thereto instead of by means of the plunging motion now most commonly used with submarine boats. By having the boat descend or rise on an even keel the torpedoes will always 25 be pointed in approximately the right angle relative to the horizontal plane. This rising or descending on an even keel is secured by means of the immersion mechanism shown in Figs. 1, 11, and 12, in which M represents a series of 30 immersion-rudders which are pivoted on the braces B', connecting the guard-rails B to the hull of the boat. These rudders are connected by tillers M' to the bars M², there being one bar on each side of the boat and three rudders 35 being shown; but the number of rudders may be increased or decreased at will. These bars are moved by levers M³, which are connected to ropes N, wound on drums O on the shaft O², which shaft carries the immersion- 40 wheel O'. These ropes are kept taut by being rove over drums P. Thus it will be seen that by means of a single hand-wheel O' all of the immersion-rudders may be operated, and the boat may be caused either to rise or descend 45 always on an even keel. In addition to these immersion-rudders the ordinary diving-rudders (not shown) may be used to bring the boat to an even keel, as in the usual way with submarine boats, but this result may also be 50 accomplished by means of the detachable weights Q, which are suspended from removable bolts q, passing through the flanges a in the bottom of the boat, as shown in Figs. 1, 2, and 10. The trim of the boat may be altered 55 by detaching these weights from forward or aft, as the case may be, or by shifting the position of the same. This can readily be done from time to time when opportunity presents; but, like other adjustments incident 60 to torpedo warfare, it would of course have to

be attended to at other times than when in action. The trim of the boat may also be altered by means of the ballast-tanks, which will be hereinafter described.

The hatch A' at the top of the boat is normally closed by a cover R, hinged, as at r, and provided with a series of glass plates r', affording an all-around view for the captain or helmsman of the boat. This hatch-cover is also provided with a glass pane or lens r² in 75 the upper portion thereof, as shown in Figs. 4 and 5, whereby the captain or helmsman may look forward when the hatch-cover is raised, as would be the case when running awash. Side curtains may also be provided, 80 such as r³, to keep the spray out of the hatch-opening when running awash, or a complete hood may be substituted for these curtains, if desired.

In the bottom of the boat I provide suitable 85 ballast-tanks T, which are separated by partitions t t'. In Fig. 13 I have shown four of such tanks, with means for filling the same by the inflow of the water of flotation and of emptying the same either by a pump operated by the motive power of the ship or by an auxiliary pump operated by flasks of compressed air. I have provided this dual arrangement, so that if the machinery of the vessel should get out of order from any cause 95 the boat may be caused to float to the surface by emptying the ballast-tanks by means of an independent source of power. Fig. 13 shows diagrammatically such a means, in which T represents the ballast-tanks separated into four 100 compartments by the partitions t and t', into each of which projects a suitable pipe for filling and emptying the same, such as U, U', U², and U³. Each of these pipes is connected outboard by means of the inlet-pipe u' and is 105 connected to a main V by means of a short pipe u². The tank may be connected either to the water outboard or to the main V by means of a suitable two-way valve u. The main V is connected at one end to the pump 110 W, which is driven by the eccentric Z from the source of power of the boat, and this pump delivers outboard the water drawn from the tank or tanks through the pipe X past the valve x. The valve x may be closed at the 115 same time with the valve v by means of a hand-rod Y, and thus all communication from the main V to the pump W and from the pipe X to the pump W may be cut off when desired. The main V is also connected at its 120 other end to a pump 1, which is normally shut off from the main V by means of the valve r'. This pump 1 delivers water outboard through the pipe 2 and is driven by means of a suitable cylinder 1^a, supplied with fluid-pressure 125 from the pipe 3, which receives the same from the air-flasks 4 and pipes 5, which pipes open into the pipe 3 past the valve 6. Thus it will be seen that the ballast-tanks may be separately or simultaneously filled from the out- 130

side by the inflow of the water of flotation or may be separately or simultaneously emptied by means of the normal motive power of the boat or by means of an independent pump actuated from a source of independent power.

5 If the boat is run by compressed air, of course the same source of air-supply may be used to drive the auxiliary pump for emptying the ballast-tanks, or the compressed air may be used to blow the water out of one or more of the ballast-tanks, as is well known in the art.

10 The boat is preferably provided with suitable eyes a^1 for convenience in hoisting out of or lowering into the water. A suitable sight a^2 may be provided for the convenience of the helmsman.

15 The boat is normally intended to be hoisted out of the water either on the dock or aboard the ship and to be launched in clearing for action or whenever desired. The torpedoes are preferably secured in place, the weights adjusted, and the boat gotten ready for use when out of water, and when lowered into the water the boat is leveled by means of the ballast-tanks and is then ready for action.

20 It will be obvious that various modifications might be made in the herein-described apparatus which could be used without departing from the spirit of my invention.

25 Having thus described my invention, what I claim, and desire to secure by Letters Patent of the United States, is—

30 1. In a submarine torpedo-boat, the combination with a series of frames grouped symmetrically on opposite sides of and exterior to the boat, and torpedoes mounted in said frames, of means for securing the torpedoes in said frames and for releasing the torpedoes therefrom when desired, substantially as de-

35 scribed.

2. In a submarine boat, the combination with a series of frames grouped symmetrically on opposite sides of and exterior to the boat, and torpedoes mounted in said frames, of means carried by said frames for locking the torpedoes therein, means for releasing each torpedo when desired, and spring-actuated means for moving the torpedo forward and for setting the motive power of the torpedo

40 in operation, substantially as described.

45 3. In a submarine torpedo-boat, the combination with a series of frames made in two parts and hinged together grouped symmetrically on opposite sides of and secured to the exterior of the hull of the boat, torpedoes mounted in said frames, means carried by said frames for holding the torpedoes therein until released, and means for releasing the torpedo, with spring-operated means for moving the same in the forward direction and for starting the motive power of the torpedo, substantially as described.

50 4. In a submarine torpedo-boat, the combination with a series of frames grouped symmetrically on opposite sides of and exterior

to the boat, and torpedoes mounted in said frames, of means for securing the torpedoes in said frames and means operated from the interior of the boat for releasing the torpedoes from said frames when desired, substantially as described.

55 5. In a submarine boat, the combination with a series of frames grouped symmetrically on opposite sides of and exterior to the boat, and torpedoes mounted in said frames, of means carried by said frames for locking the torpedoes therein, means operated from the interior of the boat for releasing each torpedo when desired, and spring-actuated means also operated from the interior of the boat 80 for moving the torpedo forward and for setting the motive power of the torpedo in operation, substantially as described.

60 6. In a submarine torpedo-boat, the combination with a series of frames made in two parts and hinged together grouped symmetrically on opposite sides of and secured to the exterior of the hull of the boat, torpedoes mounted in said frames, means carried by said frames for holding the torpedoes therein until released, and means operated from the interior for releasing the torpedo, with spring-operated means also operated from the interior of the boat for moving the same in the forward direction and for starting the motive 95 power of the torpedo, substantially as described.

65 7. In a submarine torpedo-boat, the combination with a series of frames grouped symmetrically on opposite sides of and exterior to the boat, and torpedoes mounted in said frames, of means for securing the torpedoes in said frames and spring-operated means controlled from the interior of the boat for releasing the torpedoes therefrom when desired, substantially as described.

70 8. In a submarine boat, the combination with a series of frames grouped symmetrically on opposite sides of and exterior to the boat, and torpedoes mounted in said frames, of means carried by said frames for locking the torpedoes therein, means controlled from the interior of the boat for releasing each torpedo when desired, and means for moving the torpedo forward and for setting the motive 110 power of the torpedo in operation, substantially as described.

75 9. In a submarine boat, the combination with a series of frames made in two parts and hinged together grouped symmetrically on opposite sides of and secured to the exterior of the hull of the boat, torpedoes mounted in said frames, means carried by said frames for holding the torpedo therein until released, means controlled from the interior of the boat 120 for releasing the torpedo, and means for moving the torpedo in the forward direction and for starting the motive power of the torpedo, substantially as described.

80 10. In a submarine boat, the combination

- with a series of frames made in two parts and hinged together grouped symmetrically on opposite sides of and secured to the exterior of the hull of the boat, torpedoes mounted in said frames, means carried by said frames for holding the torpedoes therein until released, and means operated from the interior of the boat for simultaneously releasing the torpedo and for moving the same in the forward direction, with means operated by the forward motion of the torpedo for starting its motive power, substantially as described.
11. In a submarine torpedo-boat, the combination with a series of frames grouped symmetrically on opposite sides of and exterior to the boat, and torpedoes mounted in said frames, of means for securing the torpedoes in said frames, and means operated from the interior of the boat for simultaneously releasing the torpedo and for moving the same in the forward direction, with means operated by the forward motion of the torpedo for starting its motive power, substantially as described.
12. In a submarine boat, the combination with a series of frames grouped symmetrically on opposite sides of and exterior to the boat, and torpedoes mounted in said frames, of means carried by said frames for locking the torpedoes therein, and means operated from the interior of the boat for simultaneously releasing the torpedo and for moving the same in the forward direction, with means operated by the forward motion of the torpedo for starting its motive power, substantially as described.
13. In a submarine torpedo-boat, the combination with a series of frames made in two parts and hinged together grouped symmetrically on opposite sides of and secured to the exterior of the hull of the boat, torpedoes mounted in said frames, means carried by said frames for holding the torpedoes therein until released, and means operated from the interior of the boat for simultaneously releasing the torpedo and for moving the same in the forward direction, with means operated by the forward motion of the torpedo for starting its motive power, substantially as described.
14. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, and means operated from within the boat for simultaneously moving both of said rods and thereby simultaneously operating all of said immersion-rudders, substantially as described.
15. In a submarine torpedo-boat, the combination with the hull of the boat, of a guard-rail mounted exterior to the hull of the boat,
- 5 10 15 20 25 30 35 40 45 50 55 60 65 70 75 80 85 90 95 100 105 110 115 120 125 130
- a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, substantially as described.
16. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, with a drum and rope for operating said lever, substantially as described.
17. In a submarine torpedo-boat, the combination with a guard-rail exterior to the hull of the boat, of a series of torpedo-frames connected to said guard-rail and to the hull of the boat, with torpedoes detachably mounted therein, a series of immersion-rudders mounted between the hull of the boat and said guard-rail, and means operated from the interior of the boat for controlling said immersion-rudders, substantially as described.
18. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and means operated from within the boat for simultaneously moving both of said rods and thereby simultaneously operating all of said immersion-rudders, substantially as described.
19. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, substantially as described.
20. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a se-

ries of immersion-rudders pivoted between said guard-rail and said hull, tillers for said rudders mounted exterior to the boat, a rod on each side of the boat connected to all of 5 the tillers on that side, and a lever mounted in the interior of the boat and simultaneously operating both of said rods, with a drum and rope for operating said lever, substantially as described.

21. In a submarine torpedo-boat, the combination with the hull of the boat, of a guard-rail mounted exterior to the hull of the boat, a series of immersion-rudders pivoted between said guard-rail and said hull, tillers for said 15 rudders mounted exterior to the boat, a rod on each side of the boat connected to all of the tillers on that side, means operated from within the boat for simultaneously moving both of said rods and thereby simultaneously 20 operating all of said immersion-rudders, and means for bringing said boat to an even keel, substantially as described.

22. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of 30 the tillers on that side, and a lever mounted in the interior of the boat and simultaneously operating both of said rods, and means for bringing said boat to an even keel, substantially as described.

23. In a submarine torpedo-boat, the combination with the hull of the boat, of a guard-rail mounted exterior to the hull of the boat, a series of immersion-rudders pivoted between said guard-rail and said hull, tillers for said 40 rudders mounted exterior to the boat, a rod on each side of the boat connected to all of the tillers on that side, and a lever mounted in the interior of the boat and simultaneously operating both of said rods, with a drum and rope for operating said lever, and means for bringing said boat to an even keel, substantially as described.

24. In a submarine torpedo-boat, the combination with a guard-rail exterior to the hull 50 of the boat, of a series of torpedo-frames connected to said guard-rail and to the hull of the boat, with torpedoes detachably mounted therein, a series of immersion-rudders mounted between the hull of the boat and said guard-

55 rail, means operated from the interior of the boat for controlling said immersion-rudders, and means for bringing said boat to an even keel, substantially as described.

25. In a submarine torpedo-boat, the combination with the hull of the boat, of a guard-rail mounted exterior to the hull of the boat, of a series of torpedo-frames connected to said guard-rail and to the hull of the boat, with 60 torpedoes detachably mounted therein, a series of immersion-rudders pivoted between

said guard-rail and said hull, tillers for said rudders mounted exterior to the boat, a rod on each side of the boat connected to all of the tillers on that side, means operated from within the boat for simultaneously moving both of said rods and thereby simultaneously operating all of said immersion-rudders, and means for bringing said boat to an even keel, substantially as described.

26. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, and means for bringing said boat to an even keel, substantially as described.

27. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, with a drum and rope for operating said lever, and means for bringing said boat to an even keel, substantially as described.

28. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, means operated from within the boat for simultaneously moving both of said rods and thereby simultaneously operating all of said immersion-rudders, and means for adjusting the trim of said boat in a fore-and-aft direction and athwartships, substantially as described.

29. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, a lever mounted in the interior of the boat and simultaneously operating both of said rods, and means for adjusting the trim of said boat both in a fore-and-

aft direction and athwartships, substantially as described.

30. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, a lever mounted in the interior of the boat and simultaneously operating both of said rods, with a drum and rope for operating said lever, and means for adjusting the trim of said boat both in a fore-and-aft direction and athwartships, substantially as described.

31. In a submarine torpedo-boat, the combination with a guard-rail exterior to the hull of the boat, of a series of torpedo-frames connected to said guard-rail and to the hull of the boat, with torpedoes detachably mounted therein, a series of immersion-rudders mounted between the hull of the boat and said guard-rail, means operated from the interior of the boat for controlling said immersion-rudders, and means for adjusting the trim of said boat both in a fore-and-aft direction and athwartships, substantially as described.

32. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, means operated from within the boat for simultaneously moving both of said rods and thereby simultaneously operating all of said immersion-rudders, and means for adjusting the trim of said boat in a fore-and-aft direction and athwartships, substantially as described.

33. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, a lever mounted in the interior of the boat and simultaneously operating both of said rods, and means for adjusting the trim of said boat in a fore-and-aft direction and athwartships, substantially as described.

34. In a submarine torpedo-boat, the combination with the hull of the boat, of a guard-rail mounted exterior to the hull of the boat,

of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, a lever mounted in the interior of the boat and simultaneously operating both of said rods, with a drum and rope for operating said lever, and means for adjusting the trim of said boat both in a fore-and-aft direction and athwartships, substantially as described.

35. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, means operated from within the boat for simultaneously moving both of said rods and thereby simultaneously operating all of said immersion-rudders, and ballast-tanks and detachable weights for bringing said boat to an even keel, and trimming same laterally, substantially as described.

36. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, and ballast-tanks and detachable weights for bringing said boat to an even keel, and trimming same laterally, substantially as described.

37. In a submarine torpedo-boat, the combination with the hull of the boat, of a guard-rail mounted exterior to the hull of the boat, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, with a drum and rope for operating said lever, and ballast-tanks and detachable weights for bringing said boat to an even keel, and trimming same laterally, substantially as described.

38. In a submarine torpedo-boat, the combination with a guard-rail exterior to the hull of the boat, of a series of torpedo-frames connected to said guard-rail and to the hull of the boat, with torpedoes detachably mounted therein, a series of immersion-rudders mounted between the hull of the boat and said guard-rail, means operated from the interior of the boat for controlling said immersion-rudders,

and ballast-tanks and detachable weights for bringing said boat to an even keel, and trimming same laterally, substantially as described.

39. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, means operated from within the boat for simultaneously moving both of said rods and thereby simultaneously operating all of said immersion-rudders, and ballast-tanks and detachable weights for bringing said boat to an even keel, and trimming same laterally, substantially as described.

40. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, and ballast-tanks and detachable weights for bringing said boat to an even keel, and trimming same laterally, substantially as described.

41. In a submarine torpedo-boat, the combination with the hull of the boat, of a guard-rail mounted exterior to the hull of the boat, of a series of torpedo-frames connected to said guard-rail and to the hull of the boat, with torpedoes detachably mounted therein, a series of immersion-rudders pivoted between said guard-rail and said hull, tillers for said rudders mounted exterior to the boat, a rod on each side of the boat connected to all of the tillers on that side, and a lever mounted in the interior of the boat and simultaneously operating both of said rods, with a drum and rope for operating said lever, and ballast-tanks and detachable weights for bringing said boat to an even keel, and trimming same laterally, substantially as described.

42. In a submarine boat, the combination with a series of frames mounted exterior to the boat, and torpedoes mounted in said frames, of bell-crank levers carried by said frames for locking the torpedoes therein, means operated from the interior of the boat for tripping each of said bell-crank levers and thus releasing each torpedo when desired, and spring-actuated means for moving the torpedo forward, substantially as described.

43. In a submarine torpedo-boat, the combination with a series of frames made in two

parts and hinged together secured to the exterior of the hull of the boat, torpedoes mounted in said frames, of bell-crank levers carried by said frames for locking the torpedoes therein, means operated from the interior of the boat for tripping each of said bell-crank levers and thus releasing each torpedo when desired, and spring-actuated means for moving the torpedo forward, substantially as described.

44. In a submarine torpedo-boat, the combination with a series of frames mounted exterior to the boat, and torpedoes mounted in said frames, of means for securing the torpedoes in said frames, and means operated from the interior of the boat for releasing and discharging the torpedoes from said frames when desired, comprising a spring-operated drum, a ratchet-and-pawl arrangement normally locking the same, a hand-lever mounted in the boat and controlling said ratchet-and-pawl arrangement, a bell-crank lever for releasing the torpedo, automatically operated by said drum, and a rope wound on said drum and adapted to haul the torpedo forward when released, substantially as described.

45. In a submarine boat, the combination with a series of frames grouped symmetrically on opposite sides of and exterior to the boat, and torpedoes mounted in said frames, of means carried by said frames for locking the torpedoes therein, means operated from the interior of the boat for releasing each torpedo when desired, and a spring-actuated drum with a rope wound thereon also operated from the interior of the boat for moving the torpedo forward when released, substantially as described.

46. In a submarine torpedo-boat, the combination with a series of frames grouped symmetrically on opposite sides of and exterior to the boat, and torpedoes mounted in said frames, of means for securing the torpedoes in said frames and spring-operated means controlled from the interior of the boat for releasing the torpedoes therefrom when desired, means for starting the torpedo forward, and means automatically operated by the forward motion of the torpedo for starting the motive power of the torpedo, substantially as described.

47. In a submarine boat, the combination with a series of frames grouped symmetrically on opposite sides of and exterior to the boat, and torpedoes mounted in said frames, of bell-crank levers carried by said frames for locking the torpedoes therein, means controlled from the interior of the boat for moving each of said bell-crank levers and thus releasing each torpedo when desired, and a spring-impressed rope for starting the torpedo forward, substantially as described.

48. In a submarine torpedo-boat, the combination with a series of frames grouped symmetrically on opposite sides of and exterior

to the boat and provided with longitudinal guide-grooves, and torpedoes mounted in said frames provided with lugs projecting into said guide-grooves, of means for securing the torpedoes in said frames, and for releasing the torpedoes therefrom when desired, substantially as described.

49. In a submarine boat, the combination with a series of frames grouped symmetrically on opposite sides of and exterior to the boat and provided with longitudinal guide-grooves, and torpedoes mounted in said frames provided with lugs projecting into said guide-grooves, of means carried by said frames for locking the torpedoes therein, means for releasing each torpedo when desired, and spring-actuated means for moving the torpedo forward, substantially as described.

50. In a submarine torpedo-boat, the com-

bination with a series of frames made in two parts and hinged together grouped symmetrically on opposite sides of and secured to the exterior of the hull of the boat with guide-grooves in said frames, torpedoes mounted in said frames provided with lugs engaging in said guide-grooves, means carried by said frames for holding the torpedoes therein until released, and means for releasing the torpedo, with spring-operated means for moving the same in the forward direction, substantially as described.

In testimony whereof I affix my signature in presence of two witnesses.

JOHN J. HARPAIN.
